Primary Examiner—Brian N. Vinson**[57]****CLAIM**

The ornamental design for a suspended pivotal bike storage rack, as shown and described.

DESCRIPTION

FIG. 1 is a perspective view of a suspended pivotal bike storage rack showing my new design;

FIG. 2 is a front elevation view thereof;

FIG. 3 is a top plan view thereof;

FIG. 4 is a side elevation view thereof;

FIG. 5 is a side elevation view showing the opposite side of FIG. 4;

FIG. 6 is an end elevation view of the rear of the suspended pivotal bike storage rack;

FIG. 7 is a bottom plan view thereof; and,

FIG. 8 is a perspective view of the suspended pivotal bike storage rack of FIG. 1 shown in an alternate position.

The broken-line disclosure of a bike in the views is for illustrative purposes only and forms no part of the claimed design.
